US0D1111008S

(12) **United States Design Patent** (10) **Patent No.:** **US D1,111,008 S**
(45) **Date of Patent:** **** Feb. 3, 2026**

(54) **DISPLAY DEVICE**

(71) Applicant: **SAMSUNG DISPLAY CO., LTD.**,
Yongin-si (KR)

(72) Inventors: **Ho Yeon Yu**, Yongin-si (KR); **Hyeon Sook Jeong**, Yongin-si (KR); **Hyun Gu Kim**, Yongin-si (KR)

(73) Assignee: **Samsung Display Co., Ltd.**, Yongin-si (KR)

(**) Term: **15 Years**

(21) Appl. No.: **29/980,802**

(22) Filed: **Dec. 26, 2024**

Related U.S. Application Data

(63) Continuation of application No. 29/853,642, filed on Sep. 16, 2022, now Pat. No. Des. 1,055,912.

(30) **Foreign Application Priority Data**

Mar. 16, 2022 (KR) 30-2022-0010238

(57) **CLAIM**

The ornamental design for a display device, as shown and described.

DESCRIPTION

FIG. 1 is a perspective view of a display device according to the present design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the display device shown in a first alternate configuration; and,

FIG. 9 is a perspective view thereof, showing the display device shown in a second alternate configuration.

In the drawings, the broken lines illustrate portions of the display device that form no part of the claimed design.

1 Claim, 9 Drawing Sheets
